UNITED STATES PATENT OFFICE.

JOHN H. WOODARD, OF LAPEER, MICHIGAN.

WHIFFLETREE.

SPECIFICATION forming part of Letters Patent No. 369,625, dated September 6, 1887.

Application filed July 18, 1887. Serial No. 244,621. (No model.)

To all whom it may concern:

Be it known that I, JOHN H. WOODARD, a citizen of the United States, residing at the city of Lapeer, in the county of Lapeer and State of Michigan, have invented certain new and useful Improvements in Whiffletrees; and I do hereby declare the following to be a full, clear, and exact description of the invention, such as will enable others skilled in the art to 10 which it appertains to make and use the same.

Figure 1 is a perspective view of the present device. Fig. 2 is a detail in perspective of one end of the device shown in Fig. 1. Fig. 3 is a detail in perspective showing the end 15 in process of construction—that is, before the slit parts of the knuckle are hammered down; Figs. 4 and 5, details in section of the knuckle and the screw-threaded end of the body of the device.

20 This invention relates to that class of devices known as "singletrees" or "whiffletrees;" and the points of novelty consist in the construction of the several parts and in their combination as a whole, all as will now be more 25 fully set out and explained, reference being had to the accompanying drawings.

In the drawings, A denotes the body of this device, which is made of gas-pipe, each end of which is screw-threaded at a. Upon each of 30 these screw-threaded ends is placed the metal knuckle B, which is internally screw-threaded to adapt it to fit upon the end of the body A. The outer end of each knuckle has a slit, b, and into these slits the ends of the metal yoke 35 C are fitted in any suitable way after the knuckles have been screwed upon the body A; and in order to retain the end of the yoke securely within these slits, and to make a good

finish at this point, the sides b' of the slits are hammered down over the end of the yoke C, 40 just above the eye c of the yoke. In this eye are placed the usual hooks, D. The yoke C is bent centrally, so as to provide at c' an eye to attach the singletree to the carriage or vehicle. Preferably the sides of the yoke in- 45 cline from c' toward the ends of the body; but this is not absolutely necessary.

It will be obvious that many changes in the mere mechanical details of the structure of this device can be made without departing 50 in any essential degree from the nature and scope of the invention as illustrated and as above described.

Having now described this invention, what I consider new, and desire to secure by Letters Patent, is—

1. A singletree consisting of a metal body, A, having knuckles B, internally screw-threaded and slit at their outer ends, attached to each end and combined with the yoke C, 60 substantially in the manner and for the purpose set forth.

2. As a new article of manufacture, a singletree consisting of the gas-pipe body A, having metal knuckles B, slit at their ends and 65 secured upon the ends of the part A and combined with the yoke C, having eyes c and c', the slit ends of the knuckle being hammered over the outer ends of the yoke C.

In testimony whereof I affix my signature in 70 presence of two witnesses.

JOHN H. WOODARD.

Witnesses:

FRANK MILLIS,
ENOCH C. WHITE.
